UNITED STATES PATENT OFFICE

JOHN M. HUGHES, OF CINCINNATI, OHIO

VALVE

Application filed April 10, 1930. Serial No. 443,138.

The present invention relates to valves and more particularly to multiple valves which, while susceptible of other uses, are particularly well adapted for use on locomotives for control of steam to the blowers at the smoke stacks and the smoke-consuming devices in the fire-boxes.

It is, at the present time, quite common to provide separate cab fittings, that is, separate valves or units in the locomotive cab for the control of steam to the blower and to the fire box. This is not only expensive practice, but also makes a great many joints which should be kept steam tight and also packing glands requiring attention from time to time. It is one of the objects of the present invention to embody in a single unit, two valves operable by a single handle and with ports so arranged as to conveniently make connections with the steam pipe communicating with the boiler and leading down in front of the rear boiler end, and to the blower pipe and induction pipe connected with the smoke-consumer. This latter pipe usually leads down from a point adjacent the upper rear left end of the boiler and branches to various jets or other outlets for introducing steam or steam and air over or relative to the fire bed.

Another object of the invention is to provide a multiple valve which makes necessary the opening of the valve port for delivery of steam to the fire box, if the fireman desires an adequate supply or full capacity of steam to be delivered to the blower when the engine is shut off, in order to prevent the smoke and gases from trailing back over the train and coming into the cab. In practice it is found that firemen or engineers sometimes object to using the smoke consumer, due for instance to the attendant noise resulting from its use.

A further object of the invention is to provide a multiple valve including a cut out valve element in the port for delivery of steam to the fire box, so that this valve element may be closed by an authorized person when the boiler is being inspected, without liability of scalding the boiler inspector should some one accidentally operate the main handle of the valve or if it should be desired to use the blower and positively prevent delivery of

steam to the fire box. This cut out valve is so arranged as a part of the valve unit that it requires no extra fitting and is constructed so that it cannot be readily operated by an unauthorized person without detection. 55

Other objects and advantages of the invention will appear in the following detailed description, taken in connection with the accompanying drawings, forming a part of this specification and in which drawings: 60

Figure 1 is a view partly in central vertical section and partly in elevation showing a multiple valve constructed according to my invention, two of the valve discs being shown in seated position and the cut out valve being 65 shown open.

Figure 2 is an elevation of the valve.

Figure 3 is a view similar to Figure 1 but showing another of the valves unseated.

Figure 4 is a similar view showing the two 70 main valves unseated, and the cut out valve seated.

In the drawings, wherein similar characters refer to similar parts thruout the views, A designates the valve body including a globe 75 portion B, oppositely disposed lateral extensions C and D projecting therefrom, and an extension E projecting downwardly from the globe portion; F, G and H valve discs; J means for operating valve F; K a lost motion device connecting valves F and G whereby the latter will be opened only after the former has been opened to a predetermined extent and closed in advance of the valve F; 80 and L, means for operating valve H. 85

Extension C is provided with an inlet port 5; extension D with an outlet port 6, which may communicate with the blower, not shown in the drawings; and extension E provided with a port 7 for communication with the smoke consuming apparatus, also not shown in the drawings. Between the ports 5 and 6 is a partition 8 provided with an opening 9 having an upwardly facing valve seat 10 for valve disc F and between ports 5 and 7 is a partition 11 having an upwardly facing valve seat 12 for valve disc G, the seats 10 and 12 being co-axial. In port 7 there is a partition 13 having a valve seat 14 for the valve disc H, the latter valve being the cutout intended for 100

use when it is desired to positively prevent the passage of steam from the multiple valve to the induction tube or smoke consuming apparatus.

- 5 Means J for operating the valve K may comprise a screw stem 16 having screw threaded engagement with a bonnet 17, as at 18, the lower end of the stem being provided with spaced flanges 19 and 20; and a hand 10 wheel 21 at the upper end of the screw stem 16. The bonnet 17 may be retained in place by a connecting nut 22 having screw threaded connection with the globe portion B in the usual manner. The upper end of the bonnet 15 17 may be provided with a packing nut 23, gland 24 and packing ring 25, all of which may be of conventional design. As suitable means for connecting the valve disc F to the screw stem 16, the former may be provided 20 with a recess 30 receiving the flange 19, this recess being open at the top and at the side as shown in Figures 1 and 4 in order that the valve disc may be slipped laterally into place with the flange 19, accommodated in the recess. A pin 31 extending transversely thru the screw stem has its ends received in recesses 25 32 thus causing the valve disc to rotate with the screw stem.

The lost motion device K in the example shown comprises a stem 33 provided with screw threads 34 at its lower end, an upper stop 35 carried by threads 34, a lower stop 36 carried by said threads, the stops 35 and 36 being separated a predetermined distance, 35 and an expansion spring 37 bearing upon valve G and accommodated at its upper end in a recess 38 formed in the lower portion of valve F, the stem 33 extending thru a central opening 40' in valve disc G.

- 40 In Figure 1 both valves F and G are seated and it is to be observed that, upon rotation of the hand wheel 21, valve F will be lifted from its seat 10 permitting steam to pass from port 5 thru opening 9 to port 6, as may be observed from Figure 3, but there is no motion transmitted to the valve G until the lower stop 36 engages the lower portion of valve D. Upon such engagement and further rotation of the hand wheel 21, the valve 45 D will be lifted from its seat 12, as shown in Figure 4 and then steam will also pass thru port 7 if valve H is unseated. In the example shown approximately a turn and a half of the hand wheel will unseat the valve F to the extent shown in Figure 3, and further movement of the hand wheel with the view of further opening the valve will cause movement of valve G. Thus if the fireman desires full capacity steam to be delivered to 50 the blower when the engine is shut off, in order to prevent smoke and gases from trailing back over the train and coming into the cab, he must also introduce steam into the smoke consumer or induction tube as previously mentioned.

The valve H may be provided with a screw stem 40 having a key head 41, and has screw threaded engagement as at 42 with a bonnet 43 secured to the extension E as by connecting nut 44. In the example shown, as a means to guard against easy manipulation of valve H, a packing nut 45 is provided having a flange 46 extending about the headed end of the screw stem 40, thus providing a recess 47 in which the head 41 is disposed when the valve H is fully open. The packing nut 45 has screw threaded engagement with the bonnet 43 and compresses a packing ring 48 about the screw stem. The extension E may be provided with an eye 49 to receive a wire 50 having a seal 51, the wire also being received in an eye 52 carried by the packing nut 45, the wire being looped thru these eyes 49 and 52 and the end portions embedded in seal 51. This serves as means to prevent tampering with the valve without detection.

When it is desired to inspect the boiler and there is liability of scalding the boiler inspector in the event that hand wheel 21 is rotated to open the valves F and G, a suitable key, not shown in the drawings, may be used to close valve H, as shown in Figure 4 of the drawings which then prevents passage of steam to the fire box even the valve G be open. This valve H may also be used when making repairs to the smoke consuming apparatus or in the event that there should be a leak in the induction tube and it is desired to use the blower during the trip to the engine house, where repairs are to be made.

It is to be observed that the ports 5, 6 and 7 extend from the globe portion B of the valve in such a way that the pipe leading from the top of the boiler may be readily connected to the valve body, and the pipe leading to the blower may extend laterally from the valve and forwardly to the front of the locomotive. The usual induction tube may extend downwardly from the very bottom of the valve thus providing a compact and neat arrangement, doing away with a number of cab fittings now in common use.

While I have herein disclosed specific means for operating valve F and a specific lost motion device between the valves F and G whereby the former is opened in advance of the latter, and the latter closed in advance of the former, it is to be understood that such is merely by way of example and changes may be made in detail without departing from the spirit of the invention as claimed.

I claim:

1. A multiple valve structure provided with an inlet port and two outlet ports, a blower valve disposed to control communication between the inlet port and one of the outlet ports, an induction tube valve disposed to control communication between the inlet port and the other of the outlet ports, a lost

motion device operatively connecting the valves, and means below the valves for adjusting the amplitude of lost motion of the lost motion device whereby adjustment may be had as to the extent to which the blower valve is opened before the operating means becomes effective relative to the induction tube valve.

2. A multiple valve structure provided with an inlet port and two outlet ports, a blower valve disposed to control communication between the inlet port and one of the outlet ports, an induction tube valve disposed to control communication between the inlet port and the other of the outlet ports, said valves disposed one above the other, a lost motion device operatively connecting the valves, and means below the lowermost valve for adjusting the amplitude of lost motion of the lost motion device whereby adjustment may be had as to the extent to which the blower valve is opened before the operating means becomes effective relative to the induction tube valve.

25 JOHN M. HUGHES.
